UNITED STATES PATENT OFFICE.

BUEL H. CANADY, OF WINSLOW, ARIZONA.

REMOVABLE BEARING-PLATE.

1,347,248.

Specification of Letters Patent. Patented July 20, 1920.

Application filed January 15, 1920. Serial No. 351,681.

To all whom it may concern:

Be it known that I, BUEL H. CANADY, a citizen of the United States, residing at Winslow, in the county of Navajo and State of Arizona, have invented certain new and useful Improvements in Removable Bearing-Plates, of which the following is a specification.

My invention relates to improvements in driving boxes for railway locomotives, trucks, trailers or the like, wherein the boxes are arranged upon the inner or outer sides of the wheels and have means to contact with the hubs of the wheels, to control the side play of the wheels.

An important object of the invention is to provide means of the above mentioned character, whereby the removable end bearing plate may be separated from the box, without dropping the wheels or removing the box.

A further object of the invention is to provide means for connecting the removable bearing plate with the end of the box, in a manner to firmly clamp these parts together, and to permit of a vertical movement of the bearing plate, upon its removal.

A further object of the invention is to provide apparatus of the above mentioned character, which is simple in construction, inexpensive to manufacture, strong and durable.

Other objects and advantages of the invention will be apparent during the course of the following description.

In the accompanying drawings forming a part of this specification, and in which like numerals are employed to designate like parts throughout the same,

40 Figure 1 is a transverse section taken on line 1-1 of Fig. 2,

Fig. 2 is a side elevation of the apparatus embodying my invention,

45 Fig. 3 is a longitudinal section taken on line 3-3 of Fig. 1, and,

Fig. 4 is a perspective view of the box and end bearing plate, separated, with parts broken away.

In the drawings, wherein for the purpose 50 of illustration is shown a preferred embodiment of my invention, the driving-box embodies a box or body portion 5, including an upper arch 6 and legs 7. The box 5 is provided at its ends with the usual flanges 8. This box may be of any well known or preferred type, and is arranged in the usual

manner on the pedestal of the truck frame, or the like. The numeral 9 designates an arch bearing, formed of bearing metal, such as brass or Babbitt metal. The arch bearing is held within the arch 6 in the usual manner.

The numeral 10 designates a vertically removable end bearing plate, which is adapted to be arranged in contacting relation with the outer flange 8. This end bearing plate has its outer side provided with a bearing strip 11, which may be formed of brass, Babbitt metal, or other suitable material. The bearing strip 11 may 60 be secured to the plate 10 in any suitable manner, as by means of a dove-tail joint 12, or by any other suitable means.

The outer flange 8 carries a pair of horizontally outstanding lugs 13, rigidly secured thereto, and these lugs have their upper faces 14 beveled or inclined downwardly toward the inner side, with the point 15 cut horizontally, as shown. Upper coating horizontally outstanding lugs 16 are rigidly 75 secured to the bearing plate 10, at its vertical edges, and extend laterally and inwardly beyond the same. These lugs have notches 17, providing vertical and inclined or beveled walls 18 and 19. The notches 17 receive the lugs 13, and the inclined walls 19 engage and coact with the inclined walls 14, whereby the plate 10 will be drawn inwardly, when drawn downwardly.

The lugs 13 and 16 are provided with vertical openings 20, slightly larger in diameter than bolts 21, passed therethrough, whereby these bolts may be readily withdrawn, and the upper lugs may partake of limited lateral movements with relation to the lower 85 lugs. The lower ends of the bolts 21 are screw-threaded, to engage nuts 22, and a cotter pin 23 is preferably passed through an opening in the lower end of the bolt.

The numeral 24 designates the wheel, having a hub 25, slidably engaging the strip 11.

The removable end bearing plate is provided in its top with an opening 26, for receiving a lubricant. This opening leads into a transverse opening 27, communicating with 100 grooves 28, in the face of the bearing strip 11.

In use, when the strip 11 becomes worn, the nuts 22 may be removed from the bolts 21, and the end bearing plate 10 raised vertically, and separated from the box 6. Another end bearing plate may be substituted in its place.

I also contemplate applying my invention to the ordinary box, now in use, in which event the one end of the box or wheel face bearing should be faced off for one-half to 5 three-fourths of an inch, to provide a space for the bearing plate 10. The lugs 13 may be suitably secured to the flange of the box, as by welding or the like.

It is to be understood that the form of my 10 invention herewith shown and described is to be taken as a preferred example of the same, and that various changes in the shape, size, and arrangement of parts may be resorted to without departing from the spirit of my 15 invention, or the scope of the subjoined claims.

Having thus described my invention, I claim:—

1. The combination with a journal box 20 having an outer flange, of laterally extending lugs carried by the flange and having inclined upper faces, said lugs having substantially vertical openings, a removable bearing plate to engage the flange, laterally extending 25 lugs carried by the bearing plate and extending laterally over the first named lugs, the second named lugs having notches provided with inclined faces and also having substantially vertical openings, and bolts extending 30 through the vertical openings in the two sets of lugs.

2. The combination with a journal box, of 35 lugs secured to one end thereof and having upper inclined faces, said lugs having openings formed therethrough, a removable bearing plate to engage the end of the journal box and to be separated therefrom by a vertical movement, lugs carried by the removable bearing plate and provided with inclined 40 faces to engage the first named inclined faces, the second named lugs having

openings, and bolts passing through the openings of the first and second named lugs.

3. The combination with a journal box, of 45 horizontally outstanding lugs secured there- to upon its opposite sides, said lugs having corresponding ends inclined and provided with longitudinal openings, a bearing plate to engage the end of the journal box to be separated therefrom by a vertical movement 50 with relation thereto, horizontally outstanding lugs carried by the bearing plate at the opposite ends thereof, the second named lugs having inclined faces at corresponding ends to engage the first named inclined faces and 55 having longitudinal openings, and bolts ex- tending through the longitudinal openings.

4. The combination with a journal box provided at one end with a substantially horizontally arranged lug, said lug being 60 provided at its top with an inclined face ex- tending longitudinally of the journal box and inclined downwardly toward the inner portion of the journal box, a removable bearing plate adapted for arrangement ad- 65 jacent the end of the journal box and to be separated therefrom by a vertical movement, said bearing plate having a substantially horizontally arranged lug provided upon its lower end with an inclined face extending 70 downwardly toward the inner portion of the journal box, the last named face being adapted to engage the first named inclined face, and means to draw the bearing plate downwardly with relation to the journal box. 75

In testimony whereof I affix my signature in presence of two witnesses.

BUEL H. CANADY.

Witnesses:

P. H. BROOKS,
EARL WEIDINGER.
